COMBINED ELECTRICAL SWITCH AND FUSE

Filed Nov. 2, 1927

Fig. 2.

UNITED STATES PATENT OFFICE

HAERY RODIN, OF CLEVELAND, OHIO, ASSIGNOR OF ONE-HALF TO HERMAN E. KOHEN,
OF CLEVELAND, OHIO

COMBINED ELECTRICAL SWITCH AND FUSE

Application filed November 2, 1927. Serial No. 230,622.

My invention relates to a system of electric wiring and it is an object of the same by the application of certain fixtures to provide an improved system so that a short circuit of one light will not throw the whole building in darkness but will only affect the light short circuited, all as will be hereinafter more fully described and claimed.

Referring to the accompanying drawings which are made a part hereof and of which similar reference characters indicate similar parts,

Figure 1 is a diagrammatic view of a building wired for electricity and showing the application of my improved fixtures, and

Figure 2, a central longitudinal section through a combined switch and fuse.

In the drawings reference character 10 indicates a building provided with rooms 11, 12 and 13. A main switch 14 receives current from leads 15 from a power line and the current is led through a meter 16 to a line switch 17 provided with a fuse plug 18 inserted in the hot side of the circuit. Conductors 19 and 20 carry the electric current from the switch 17 into the vicinity of the rooms 11, 12 and 13. Drop lights 21, 22 and 23 or other suitable fixtures are suspended in the rooms from the conductors 19 and 20.

The drop light 21 in room 11 is controlled by a wall switch 24 such as shown in Fig. 2. The room 11 is also provided with a combined fuse and floor plug having connections 26 and 27 with the conductors 19 and 20.

The rooms 12 and 13 may be provided with any desired fixtures, however, I have shown them provided with drop lights 22 and 23 suspended from canopies 28, a fuse plug 18 being inserted in each canopy in the hot side of the circuit.

With this construction a defect causing a short circuit in either of the rooms 11, 12 or 13 will blow out the nearest fuse and throw the respective room in darkness but will not affect adjoining rooms. For example, if a short circuit occurs at the lamp 21 or about its canopy from which it is supported, the fuse in the box associated with the switch 24 will be blown and a light or other attachment connected with the floor

plug 25 will not be affected nor will the adjoining rooms be affected. In room 12 if any short circuit occurs between the drop light 22 and the canopy it will be taken care of by the fuse plug 18 and no other light will be affected. The same is also true of the room 13. However, if the short circuit occurs above the drop light socket the fuse in the switch 17 will blow as in any ordinary systems of wiring. Of course a short circuit can hardly occur between the walls and ceiling so there will be no reason for the fuse in the safety switch 17 to blow but it is put there only as an added precaution or for safety's sake.

Unless the canopy in a room is provided with a fuse plug 18 any short circuiting of the conductors 19 and 20 will of course blow the fuse in the switch 17 requiring a trip to the basement and a renewing of the fuse in the said switch, however, any of the other fuses which blow and require changing may be changed without making a trip to the basement.

In Fig. 2 I have shown in detail the construction of my switch 24. The switch is mounted in a metallic outlet box 30 secured in position by means of screws 31 and covered by a plate 32 held in position by screws 33. The switch is comprised of a body 34 formed of porcelain or other material having good insulating qualities and provided with brackets 35 by means of which it is secured in the outlet box 30. Conductors 36 and 37 are connected at opposite ends to the porcelain body 34 and said conductors are connected by means of a toggle switch 24, conductors 38 and 39, and a socket 40 for the reception of the fuse plug 18. The conductors 38 and 39 are connected with spaced parallel contact segments 41 and 42 which are designed to be bridged by means of a U-shaped bridge piece 43 pivoted at 44 and adapted to be oscillated by a spring 45 and a lever 46, said lever being pivotally connected with the pivot for the switch lever 24. A cover or lid 47 for the fuse plug 18 is pivoted adjacent the switch lever 24 and the arrangement is such that it is necessary to have the switch in off position

before the cover 47 can be raised and the

fuse plug removed from its socket, thereby eliminating any danger of getting a shock while replacing a fuse plug.

The incorporation of the fuse plug with a switch will protect the switch, will prevent any fires or short circuits from doing any damage, and will also obviate the necessity of going to the basement to renew a fuse plug.

With the above arrangement a fuse may be 10 easily and safely changed by a woman or child without running to the basement and without working in a box which contains exposed wires. In case any of the fixtures will be in need of repair it will not be necessary for 15 the electrician to shut off the main switch. It will only be necessary to remove the fuse in the switch or canopy controlling this particular fixture. By doing so the occupants of the house will be able to enjoy the comforts 20 of the lights in all the other rooms and it will permit the electrician to do his work in safety without taking the chances of shock. Short circuits and other troubles may be more easily located by electricians and a considerable saving 25 in both time and expense will be the result. Likewise fuses of varying capacities may be used, as, for example, a 5 ampere fuse may be used in one of the rooms where a lamp only is to be used while a larger ampere fuse 30 may be used with a vacuum cleaner and also in the switch 17.

It will be readily understood that my combination switch and fuse 24 or floor plug and fuse 25 may be placed in any other position desired as for example directly in the floor.

It will be obvious to those skilled in the art that various changes may be made in my device without departing from the spirit of the 40 invention, and I, therefore, do not limit myself to what is shown in the drawings and described in the specification, but only as set forth in the appended claim.

Having thus fully described my said invention, what I claim as new and desire to 45 secure by Letters Patent, is:

A combined electrical switch and fuse comprising a housing, a socket for the reception of a threaded fuse plug in said housing of a 50 depth to cause the head of the fuse plug to be located without the housing when the plug is in position, a switch in said housing, an operating member for the switch disposed in close proximity to the head of the fuse plug 55 when the switch is closed, and a cover for the fuse plug pivoted between the operating member and the socket and capable of being raised only when the switch is in open position, substantially as set forth.

60 In witness whereof, I have hereunto set my hand at Cleveland, Ohio, this 26th day of October, A. D. nineteen hundred and twenty-seven.

HARRY RODIN.
